UNITED STATES PATENT OFFICE.

ROBERT S. TRYNOSKI, OF CHICAGO, ILLINOIS.

BOILED-POTATO-SLICING MACHINE.

1,417,360.

Specification of Letters Patent. Patented May 23, 1922.

Application filed December 15, 1921. Serial No. 522,642.

To all whom it may concern:

Be it known that I, ROBERT S. TRYNOSKI, a citizen of the United States, residing at Chicago, in the county of Cook and State of Illinois, have invented certain new and useful Improvements in Boiled-Potato-Slicing Machines, of which the following is a specification.

The object of this invention is to provide a new and improved machine with which boiled potatoes may be sliced, for the purpose of making potato salads.

This and other objects of this invention will be fully illustrated in the drawing, described in the specification and pointed out in the claims at the end thereof.

In the accompanying drawing:

Figure 1 is a top plan view of the potato slicing machine.

Figure 2 is a perspective view of the potato slicing machine.

In the several figures of the drawing like reference numerals indicate like parts.

For the purpose of making potato salads the potatoes are first boiled, peeled, and allowed to cool off. The cold boiled potatoes are then sliced into suitable slices and mixed with a dressing and possibly other ingredients to complete the salad. Heretofore the slicing of the potatoes has been done by hand with the result that the slices were made irregular in size. Hand slicing is also slow and expensive.

The machine forming the subject matter of this invention operates to cut the slices evenly at a rapid rate of speed never before attained by the hand method. It comprises the base or bed plate 1 on which the magazine 2 is mounted. This magazine is made up of the two sides 3 and 4, the open front end 5 and rear end formed by the movable pusher plate 6. In the sides are formed the runways 7 and 8. The pusher plate 6 is provided with a pair of guide bars 9 and 10 which project rearwardly and engage into the runways 7 and 8 for the purpose of guiding the pusher plate in a straight line horizontal movement between the sides 3 and 4 from one end to the other end thereof.

The pusher plate is moved back and forth by the connecting rod which is connected to the pusher plate with one end thereof, for which purpose the pusher plate is provided with a pair of lugs 12 and 13 in order to

form suitable bearings for the wrist pin 14 carried on the end of the connecting rod 11.

The other end of the connecting rod connects to the crank pin 15 forming part of the crank disc 16. The crank disc is keyed to the left hand end of the shaft 17 which is mounted to rotate in the bearings 18 provided on the top of the standard 19. Keyed to the right hand end of the shaft 17 is the bevel gear 20 which meshes with the bevel pinion 21 keyed to the power shaft 22. The power shaft 22 is mounted in the bearings 23 and 24 and has the hand wheel 25 keyed to one end thereof by means of which the machine is driven. Also keyed to the shaft 22 is the spur gear 26 which meshes with the pinion 27 keyed to one end of the shaft 28. The other end of the shaft 28 has the cutting wheel 29 keyed thereto by means of which the potatoes are sliced as will hereinafter be described.

Mounted in the standard 19 and projecting out from under the crank disc 16 is the stud 30. A lever 31 divided into the long arm 32 and the short arm 34 is mounted to rock on this stud. The short arm carries on its outer end the anti-friction roller 40 which is adapted to make contact with the periphery of the cam 40^A forming part of the crank disc 16.

The long arm 32 projects forward to one side of the magazine and has the links 41 and 42 connected thereto. These links connect the arm 32 with the leaves 44 and 45 which are hinged to the top of the magazine, one at the front and the other at the rear thereof.

The cam 40^A has two cam surfaces formed thereon, one which operates to rock the short arm 34 away from the center of rotation thereof, and the other which allows the arm 34 to move back toward the center of rotation of the cam. This latter motion is effected by the spring 46 which is stretched between the arm 32 and a suitable point on the bed plate of the machine. When the short arm of the lever is forced outwardly the long arm is raised and in so doing rocks the leaves 44 and 45 so as to open the top of the magazine. The magazine can then be filled with potatoes. For this purpose the top of the magazine is kept open during the rearward stroke of the pusher plate, the cam 40^A operating to

do this during one half of its revolution.

On the forward stroke of the pusher plate the cam permits the spring to pull the arm 32 back and in so doing makes the leaves 5 44 and 45 fold down over the top of the magazine to keep the potatoes in place therein. In this way the potatoes can only be forced through the open end where they are being cut into slices by the wire mesh mounted 10 at the open end 5 and the cutting wires of the cutting wheel rotating on the outside of the open end.

The cutting wheel 29 with which the potatoes are sliced as fast as they are pushed 15 through the open end of the magazine, comprises a series of radial arms 35 which branch out from their common hub 36. At the outer end these arms are curved in the direction in which the wheel is rotated besides 20 being set to project angularly to the rear toward the free end of the magazine. A cutting wire is stretched between the curved end of each of the arms and a suitable point on the hub to form a series of 25 radial cutting wires 37 which are moved past the open end of the magazine on the rotation of the cutting wheel.

The end 5 of the magazine 1 is not entirely open but has a coarse wire netting 38 placed across it. This netting does not obstruct the potatoes as they are forced 30 through the end 5 ready to be sliced by the cutting wires 37 but operates to cut the potatoes into horizontal sections as they are being forced therethrough. In this way the potatoes are not only cut in vertical slices 35 of even thickness but are also cut into sections lengthwise of equal dimensions. A uniform product is thus produced by the 40 machine which not only improves the appearance of the salad made with potatoes cut with this machine, but also improves the taste thereof because each slice being of the same thickness and dimension absorbs the 45 same amount of the ingredients with which the potatoes are mixed to make up the salad.

The operation of the potato slicing machine is as follows:

The potatoes after being boiled are allowed 50 to cool off so that they can be handled for the purpose of peeling them. The operator then fills the magazine 1 with these potatoes and starts to rotate the handwheel 25. This operates to move the pusher plate 55 into the magazine while the cover is placed over it to prevent the potatoes from being forced out through the top of the magazine. The cover is held down over the magazine during the forward movement of the pusher 60 plate caused by the further rotation of the hand wheel. At the same time the pusher plate is being moved forward to force the potatoes through the wire mesh at the open end of the magazine, the cutting wheel is 65 being rotated, and as each of the cutting

wires swings past the front of the magazine, the potatoes forced out of the open end of the magazine are being sliced off thereby.

This takes place until the pusher plate reaches the end of its forward travel and all 70 the potatoes have been forced out of the magazine thereby. On further rotation of the hand wheel by the operator the pusher plate begins to move rearwardly while the cover swings open so as to allow the operator 75 to again fill the magazine with potatoes that will be forced therethrough and cut by the cutting mechanism on the return movement of the pusher plate as heretofore pointed out. This cycle of operation repeats itself over 80 and over again as long as the hand wheel is being rotated and the magazine is being filled with potatoes.

I claim:

1. A machine for slicing boiled potatoes, 85 comprising a magazine, a pusher plate operating to slide back and forth in said magazine from one end thereof, a wire mesh at the opposite end thereof, a cutting wheel on the outside of said wire mesh, a cover over 90 said magazine, and means for simultaneously operating said pusher plate, said cutting wheel, and said cover, to hold the potatoes contained in said magazine from being forced through the top thereof, to force 95 them through said wire mesh and to cut them with said cutting wheel.

2. In a machine for slicing boiled potatoes, the combination of a bed plate, a magazine comprising a pair of sides, a wire mesh 100 closing one end of said magazine, a pusher plate forming the other end of said magazine, a connecting rod adapted to move said pusher plate in and out of said magazine, a hand wheel for operating said connecting 105 rod, a cutting wheel mounted in front of said wire mesh at one end of said magazine, said hand wheel operating to rotate said cutting wheel simultaneously with the operation of said pusher plate, a cam, a lever 110 operated by said cam, a cover for said magazine, said lever being connected to said cover, said cam being operated by said hand wheel and operating said lever to open and close said cover on said magazine. 115

3. A machine for slicing boiled potatoes, comprising a magazine, a pusher plate operating to slide back and forth in said magazine, a cutting member on the outside of said magazine, a power shaft mounted on one 120 side of said magazine parallel to the movement of said pusher plate in said magazine, a jack shaft mounted at right angles to said power shaft at the rear of said magazine, a crank disk keyed to said jack shaft, a connecting rod connecting said crank disk with said pusher plate, said cutting member being operated by said power shaft simultaneously 125 with said pusher plate.

4. A machine for slicing boiled potatoes, 130

comprising a magazine, a pusher plate operating to slide back and forth in said magazine, a cutting member on the outside of said magazine, a power shaft mounted on one side of said magazine parallel to the movement of said pusher plate in said magazine, a jack shaft mounted at right angles to said power shaft at the rear of said magazine, a crank disk keyed to said jack shaft, a connecting rod connecting said crank disk with said pusher plate, a stud mounted parallel to said jack shaft, a lever mounted to rock on said stud, a cam mounted on said jack shaft, said cam being adapted to rock said lever on said stud, a pair of links connected to the free end of said lever, a pair of covers mounted on top of said magazine one at each end thereof, said links being connected to said covers to open and close said magazine at each revolution of said crank disk, said cutting member being operated by said power shaft simultaneously with said pusher plate.

In testimony whereof I affix my signature.

ROBERT S. TRYNOSKI.
